UNITED STATES PATENT OFFICE.

CHARLES E. BENHAM, OF SCHENECTADY, NEW YORK.

KEYBOARD FOR COMPOSING-MACHINES.

1,178,124.

Specification of Letters Patent.

Patented Apr. 4, 1916.

Application filed April 16, 1914. Serial No. 832,352.

To all whom it may concern:

Be it known that I, CHARLES E. BENHAM, a citizen of the United States, residing at Schenectady, county of Schenectady, State 5 of New York, have invented certain new and useful Improvements in Keyboards for Composing-Machines, of which the following is a specification.

The present invention relates to the key 10 boards of composing machines, and in particular to those of the Lanston type. Such key boards as commonly constructed have a plurality of keys which are independently depressed and released by the operator, one 15 key being used for each type, whether space or character. These keys control elastic fluid motors, all or the greater majority of which actuate punches that perforate a paper ribbon that is subsequently used in 20 a casting machine in the formation of type. In certain instances one or more punches are omitted from their corresponding motors because unnecessary. The actuation of each key, in addition to causing one or more 25 motors and their punch rods to operate, causes the ribbon feeding mechanism to act and also the em rack and associated parts.

In prior patents of mine No. 1,099,734 dated June 9, 1914 and No. 1,106,538 dated 30 August 11, 1914 I have disclosed means whereby a given movement of one or more special keys, called repeating keys, will, when moved to a predetermined position, cause the motor or motors controlled thereby 35 to repeat their actions indefinitely. When the motors activate punches, the paper ribbon will be perforated and the feed mechanism will advance the ribbon step-by-step between motor operations. When the punches 40 are omitted the motors act as before and the paper ribbon is advanced step-by-step but without perforations.

The object of the present invention is to 45 apply this repeating feature to all of the type, space, or character keys on the board, or at least to as large a number as may be considered necessary or desirable. In other words, my aim is to make every type, space, or character key a repeating key so that any 50 predetermined type, space, or character can be repeated indefinitely.

Another and important feature of the invention is to so construct and arrange the parts that my improvement can be applied

to existing machines, of which there is a 55 very large number in existence, without substantial change or rebuilding and at a relatively small expense.

Briefly stated, in carrying out my invention I take the ordinary key board as it is 60 found and add an extra key, called for convenience a repeating controller key, which is normally idle, but coöperates with each and all of the character keys for repetition work. I also add an auxiliary motor which 65 acts in opposition to the individual motors of the punch carrying bars. This motor is regulated by the repeating controller key, the latter having two positions, an "off" when the machine works in its original way, 70 and an "on" when the machine repeats whatever character is represented by the character key when it is depressed. I may, and preferably do, add a device for stopping the automatic repetition at any predetermined time, as for example, at the end 75 of a line of the page to be printed, or at some intermediate point as in tabular work. This device is operated in conjunction with the em rack pointer and serves to stop the 80 auxiliary motor.

In the accompanying drawing which illustrates one of the embodiments of my invention, Figure 1 is a perspective view of a portion of a key board comprising machine, 85 and Fig. 2 is a diagrammatic view of the auxiliary motor and the parts immediately associated therewith.

The drawings are more or less diagrammatic to simplify the illustration and are 90 not to scale.

9 indicates one of the many ordinary type, space, or character keys which, when depressed by the operator, moves a bar 10 having projections on the under side which in 95 turn move the rods 11 mounted on the rock-shafts 12. A compressed air chest 13 is provided, and mounted therein are valves 14 which admit air to the cylinder of the reciprocating motors 15. The piston in each 100 cylinder as it moves upwardly carries with it the lever 16, bar 17, and punch 18, the latter perforating the paper ribbon 19. The punches in most instances operate in pairs, but in some instances only one may operate 105 at a time. In the case of the quad character key it is common practice to omit the punch from the bar because the corresponding per-

foration in the ribbon is unnecessary in the casting machine. The ribbon has marginal perforations 20 to receive the pins on the feed rolls 21, the latter being mounted on 5 the spindle 22. The specific means for actuating the spindle step-by-step between motor and bar movements are not illustrated because it seems unnecessary to an understanding of my invention. The arrangement 10 shown in my prior Patent No. 1,099,734 dated June 9, 1914, is satisfactory for the purpose. The ribbon passes between two die plates 23 that also serve to guide the punches.

15 To depress the bars 17 and the punches, mechanism including a tension arm 24 is provided that is actuated by a fluid motor 25 comprising a piston and cylinder. The air pressure under the piston tends at all 20 times to hold the punch bars down but is over-powered by the motors 15 when the latter are active. Connected to the tension arm by a link is a lever 26 that assists in the operation of the so-called unit rack.

25 27 indicates a lever that is connected to the usual stop mechanism for the unit rack slide.

In the front of the machine is the usual em rack 30 carrying a pointer 31 that moves 30 over the scale plate 32. Thus far the parts described are old.

Mounted on the tension arm either as an integral part, or fastened thereto, is an arm 33, the rear end of which is connected to a 35 link 34 that co-operates with the piston 35 of the auxiliary motor 35^a, the latter being of sufficient power to overcome motors 15 when assisted, for example, by the tension arm motor 25. In any event, the auxiliary motor 35^a must when active, quickly overpower 40 the motors 15. Surrounding the piston 35 of the auxiliary motor is a cylindrical valve 36 having inlet ports 37 and exhaust ports 38. The ports in the valve extend a substantial 45 distance around it to insure proper operation. The upper end of the valve is provided with an internal shoulder that is engaged by the piston in the position shown. The lower end of the valve is also provided 50 with an internal shoulder which is struck by the piston on its descent thus carrying the valve with it to control the ports, as will appear later. The valve will ordinarily stay in the position to which it is moved by 55 the piston, but as an additional precaution a friction device comprising a ball 39 and spring may be provided, the former being adapted to enter a substantially half round groove in the piston. The piston is normally 60 held in its raised position by the coiled compression spring 40.

I have illustrated a type of motor suitable for my present purposes, but the invention is not limited to the specific form shown 65 unless so stated in the claims.

41 indicates any suitable type of two-way valve and 42 a key or actuator therefor. For convenience the key 42 may be termed a "repeating controller key." When standing 70 in the position shown the supply of compressed air to the valve casing by the pipe 43 is shut off. When moved to the right, Fig. 2, air passes through the valve and pipe 44 to the cylinder of the auxiliary motor. Interposed in the pipe 44 is a valve casing 75 and valve 45, the latter being normally open, as shown in Fig. 2, and actuated by a rod and bell crank lever 46, the latter forming a part of a bar 47 extending across the front of the machine. The bar has two 80 alined pivots 48. On the bar are one or more suitable stops 49 having beveled upper faces that are adapted to be engaged by the finger 50 carried by the movable em rack 30. When the finger strikes one of the stops it 85 depresses the bar and causes the bell-crank lever and rod to shut the valve 45 and thereby automatically interrupt the passage of air to the auxiliary motor. An extension spring or equivalent device 51 normally 90 holds the bar in its raised position and the valve 45 open.

The operation of the apparatus is as follows: Assuming the repeating controller key 42 to be in the "off" position the operator depresses and releases the type, space, or character keys 9, called for convenience normal keys, one after the other in the same manner as with any other Lanston machine, and the motors act to raise the bars 17 and 95 also the punches 18 when said bars are provided with them. In any event, between each two similar movements of a motor and its bar the toothed wheels 21 feed the paper ribbon 19 one step, usually equal to the pitch 100 distance of the marginal perforations 20, and the em rack advances in the usual manner. When the finger 50 strikes a stop it will depress the bar 47 and on the actuation of the next key slide over it. This movement 105 of the bar is without effect, however, as the air supply pipe 43 is closed and the mere closing and opening of valve 45 has no effect. Whenever a character key is depressed and released the piston 35 moves down and up, 110 but this also has no effect because the air supply is cut off by the valve 41. Assuming now that the operator desires to repeat any character, the repeating controller key 42 is moved to the "on" position. It may be so arranged that it is necessary to hold the key with one finger, or it may be stable in either of its two positions. After setting this key 115 the operator depresses the desired character key, such as 9, with the result that its corresponding motor, or motors, 15 raise the punch carrying bars 17. This same action forces the piston 35 downward, first taking up the lost motion between it and the internal shoulder of the valve, and then carrying 120 125 130

the valve 36 along with it. The valve first closes the exhaust port 38 and then opens the inlet port 37 to the air in the pipe 44. This admits compressed air under the piston 35 and the latter coöperating with the piston of motor 25 starts the return movement of the tension arm 24 and pistons of motors 15, compressed air being under the latter pistons because the character key is held depressed. Just before the piston 35 reaches the upper limit of its travel it strikes the upper shoulder on the valve 36 and moves it upward with the effect of closing inlet port 37 and opening exhaust port 38. As soon as this happens the force exerted by the motors 15 predominates (compressed air acting on the under side of the pistons due to the position of the character key 9) and the punch bars again rise with the effect of moving piston 35 of the auxiliary motor downward, and the repeating action goes on indefinitely until the character key is released, or until the automatic stopping device comes into play. The upward movement of the piston is, of course, assisted to a certain extent by the spring which is under it. Said spring also serves to hold the piston and the lower end of rod 34 in contact. The stopping device comprises the pivotally supported bar 47 and coöperating parts. Assuming the device to be in operative position, the finger 50, when it has been moved by the em rack to a predetermined position, strikes one of the stops 49 which depresses the rod and causes the bell-crank lever 46 and rod to shut the valve 45, thus interrupting the supply of air to the auxiliary motor and the latter stops and with it the automatic repetition. After this the repeating controlling key may be returned to the "off" position or the repeater may be allowed to operate again after the downward pressure on bar 47 has been released.

My invention has the very great advantage of simplicity, and by its use any standard key board machine can be readily converted into a repeating key board machine, in which any character can be repeated at will and as many times as is desired. By avoiding interference with the normal working the efficiency of operation is maintained, and over and above that the amount of work done on the machine can be largely increased, particularly for tabular work. Due to the repeating feature the strain on the operator is also greatly decreased. By arranging the parts as shown the necessity of any substantial change or rebuilding is obviated.

In accordance with the provisions of the patent statutes, I have described the principle of operation of my invention, together with the apparatus which I now consider to represent the best embodiment thereof; but I desire to have it understood that the ap-

paratus shown is only illustrative, and that the invention can be carried out by other means.

What I claim as new and desire to secure by Letters Patent of the United States, is—

1. In an apparatus of the character described, the combination of a plurality of movable keys, motor actuated devices which are controlled by the keys, each device making one record for a given depression of the key, an auxiliary motor which is normally idle but acts on said devices in opposition to the other motors, and a repeating controller key for putting the auxiliary motor into and out of action.

2. In an apparatus of the character described, the combination of a plurality of normal keys, motor actuated devices for making records which are controlled in their operation by the keys, an auxiliary motor which is common to all of the devices and when energized acts in opposition to the record making movement of the particular device which responded to the movement of any particular key, and a repeating controller key for putting the auxiliary motor into and out of action.

3. In an apparatus of the character described, the combination of a plurality of movable normal keys, fluid motors controlled by the keys for making records, means acting in opposition to the motors, and a key which, when moved to a predetermined position and a normal key is actuated, causes certain of the motors and means to repeat a type character as determined by a normal key.

4. In an apparatus of the character described, the combination of a plurality of normal keys, motor actuated agents for making records that act in response to predetermined movements of the keys, a restoring means which is common to all of said agents, an auxiliary motor which is normally inactive but when energized coöperates with the restoring device to return the agent to its initial position.

5. In an apparatus of the character described, the combination of a punch bar, a motive power agent for actuating it, mechanism for restoring the agent and bar to their initial positions, a normal key controlling the action of the agent, a means arranged to move the punch bar independently and against the action of the agent, and a repeating controller key which, when moved to a predetermined position, causes the means to repeat any character as determined by the actuation of any one of the normal key.

6. In an apparatus of the character described, the combination of a plurality of punch bars, means for actuating them, mechanism for restoring the means to initial position, a plurality of normal keys acting individually to control different ele-

ments comprising said means, a motor arranged to act on all of said means, and a repeating controller key which, when moved to a predetermined position, causes the 5 motor to repeat any one of the characters as determined by a normal key.

7. In an apparatus of the character described, the combination of a punch bar, a fluid pressure motive agent for actuating it, 10 mechanism for normally restoring the agent to its initial position, a normal key which, when moved to a given position, causes the agent to act, means arranged to act in opposition to the agent which are normally inactive, and a repeating controller key which, when moved to a predetermined position, 15 puts the means into action and causes it to repeat a character as determined by the actuation of a normal key.

20 8. In an apparatus of the character described, the combination of a plurality of punch bars, fluid motors for actuating them, mechanism for restoring the bars to initial position when pressure on the motors is released, a plurality of normal keys arranged 25 individually to control different motors, a means which is normally idle and arranged to act on the bars in conjunction with said mechanism, and a repeating controller key 30 which, when moved to a predetermined position, causes said means to act in conjunction with a fluid motor to repeat a character determined by the actuation of a normal key.

35 9. In an apparatus of the character described, the combination of a punch bar, a fluid pressure motor for actuating it, mechanism for restoring the bar to place after actuation, a valve for the motor, a normal key for actuating the valve, an auxiliary 40 fluid pressure motor arranged to act on the bar and which is normally idle, valve means for the auxiliary motor, and a repeating controller key for moving the valve means to a position to cause the auxiliary motor to 45 cooperate with the first named motor to repeat the character as determined by the normal key.

50 10. In an apparatus of the character described, the combination of punch bars, motors for actuating them, mechanism for restoring the bars to initial position, normal keys for normally controlling the motors, an auxiliary motor which is normally idle, and a repeating controller key which, when 55 moved to one position, cuts the auxiliary motor out of service and when moved to another position causes the auxiliary motor to coöperate with one of the first named motors to repeat a character as determined by 60 a normal key.

65 11. In an apparatus of the character described, the combination of a plurality of punch bars, a motor for each bar, a tension arm that is common to all of said bars, a motor that tends at all times to restore all

the bars to initial position, an auxiliary motor whose movable element is connected to the tension arm, keys for controlling the first named motors in normal operation, and a repeating controller key which, when moved to a predetermined position, causes the auxiliary motor to coöperate with the restoring motor to move a bar as determined by a normal key against the force exerted by its motor.

75 12. In an apparatus of the character described, the combination of a plurality of punch bars, motors for actuating the bars, mechanism for restoring the bars to initial position, an auxiliary motor which is normally idle for causing repetition of the movements of said motors, a valve for the auxiliary motor which is moved by the movable element thereof, and a repeating key and valve for the auxiliary motor which, 80 when moved to a predetermined position, starts it into operation.

85 13. In an apparatus of the character described, the combination of a plurality of movable normal keys, mechanism controlled thereby for making ribbon records, means causing the mechanism to repeat any given record as determined by the movement of a normal key, and means for automatically stopping the repetition after a predetermined number of records have been made.

90 14. In an apparatus of the character described, the combination of a plurality of movable normal keys, mechanism responsive to key movements for making records on a 100 ribbon, a repeating controller key coöperating with the normal keys to cause said mechanism to successively repeat the same record, and means for automatically stopping the repetition by rendering the repeating key 105 ineffective.

110 15. In an apparatus of the character described, the combination of a plurality of movable normal keys, mechanism responsive to key movements for making records on a 110 ribbon, a normally idle fluid motor which coöperates with the mechanism to cause repetition of the various type characters, a repeating key for controlling its operation, and valve means for automatically shutting off the supply of fluid to the motor when it is desired to stop repetition.

115 16. In an apparatus of the character described, the combination of a punch bar, a motor for actuating it, means for restoring the bar to initial position, a key for normally controlling the motor, additional means for actuating the bar, a repeating controller key which coöperates with the normal key to cause said means to automatically actuate the bar, and a means for stopping the automatic actuation of the bar.

120 17. In an apparatus of the character described, the combination of a punch bar, a motor for actuating it, means for restoring 130

the bar to initial position, a key for normally controlling the motor, an auxiliary motor which is normally inactive for automatically actuating the bar, a repeating controller key to cause the auxiliary motor to automatically actuate the bar, and a means for cutting off the supply of energy to the auxiliary motor after it has actuated the bar a predetermined number of times.

10 18. In an apparatus of the character described, the combination of a punch bar, a motor for actuating it, means for restoring the bar to initial position, a key for normally controlling the motor, a fluid pressure motor that is normally idle for causing repetition of the bar operations, a repeating controller key and valve for admitting fluid pressure to the motor, a second valve interposed between the first and the 20 motor, and means for actuating the second valve.

19. In an apparatus of the character described, the combination of a plurality of punch bars, motors for actuating them, a mechanism for restoring the bars to initial position, keys for normally controlling the motors, an em rack, an auxiliary motor for causing repetition of any given character as determined by a normal key, a pivotally supported bar in proximity to the rack, a device moving with the rack arranged to move the bar on its pivots, a repeating controller key for controlling the auxiliary motor, and means moved by the bar for taking 35 the control of the auxiliary motor from the repeating key.

20. In an apparatus of the character described, the combination of a plurality of valves each of which is opened by a key and 40 closes when it is released, fluid motors controlled by the valves, devices actuated by the motors, a means for restoring each device to place after it has made a stroke, an auxiliary fluid motor which is normally idle 45 but assists the restoring means when active, a valve for controlling the supply of fluid to the auxiliary motor, and means for moving the valve.

21. In an apparatus of the character described, the combination of mechanism for making a plurality of ribbon records representing different characters, a plurality of normal keys, each representing a different character and which, when moved to operative position, causes the mechanism to make a ribbon record corresponding thereto, a motor which is idle during the normal operation of making ribbon records, but acts on the record forming part of said mechanism 55 to cause repetition on the ribbon record of all of said characters as represented by the normal keys, and a key for putting the motor into action whereby it acts on said mech-

anism to reproduce a ribbon record corresponding to that of the last normal key actuated. 65

22. In an apparatus of the character described, the combination of punches for making records, motors for moving the punches on their cutting stroke, a plurality of keys for controlling the motors during normal operation, a normally idle auxiliary motor which, when energized, retracts the punches in opposition to the force exerted by one or more motors, and a repeating controller key which controls the action of the auxiliary motor. 70 75

23. In an apparatus of the character described, the combination of punches for making records, motors for moving the punches on their cutting strokes, a plurality of normal keys for controlling them, means for retracting the punches when the motors are deenergized during normal operation, a plurality of normal keys for controlling the motors, an auxiliary motor means common to the punches which, when energized, move the punch or punches that have responded to the action of a normal key in opposition to said motors, and a repeating controller 90 key for the auxiliary motor means. 80 85

24. In an apparatus of the character described, the combination of punches for making records, elastic fluid motors for actuating the punches, controlling valves therefor, normal keys acting on the valves by means of which the motors are caused to actuate their coöperating punches once for every predetermined movement thereof, an auxiliary motor that is normally idle, a member for retracting the punches, a motor for actuating it, a power transmitting connection between the auxiliary motor and the member, and a key which, when operated simultaneously with a normal key, causes the 100 motor or motors controlled by said normal key to repeat its operation. 95

25. In an apparatus of the character described, the combination of a plurality of punches for making ribbon records, motors for operating them individually, means for retracting the punches when the motors are deenergized, a normally idle means which, when energized, coöperates with the retracting means to move the punches against the 110 action of the motors, keys for controlling the motors, and a key controlling said normally idle means, the said keys acting together to cause repetition of any desired character. 115

In witness whereof, I have hereunto set my hand this tenth day of April, 1914.

CHARLES E. BENHAM.
